CARTRIDGE FEED DEVICE

Heinrich Romberg, Dusseldorf, Germany, assignor to Rheinische Metallwaren- und Maschinenfabrik, Dusseldorf, Germany, a corporation of Germany

Application May 25, 1934, Serial No. 727,566
In Germany January 20, 1933

8 Claims. (Cl. 89—33)

The invention relates to cartridge feeding mechanisms for automatic firearms of the kind having a sliding barrel and a longitudinally moving breech, in which the cartridges, disposed side by side in a cartridge holder in front of the barrel chamber are passed in sequence, by means of a conveyer slide adapted to be displaced transversely to the longitudinal axis of the weapon, into the vicinity of the breech block which 5 thrusts them from the cartridge holder on the run out or forward movement, into the barrel chamber. In firearms of this kind as heretofore constructed the cartridge holder is advanced, in 10 synchronism with the succession of shots, and by the movement of the barrel, through the mean distance between the axes of two cartridges, by means of a slide reciprocated transversely to the gun incidentally to the recoil and run out movement of the barrel, which slide displaces the 15 holder by means of pawls which are effective only in the direction of advance of the holder.

As the movement of the conveyer slide for the advance of the cartridge holder is derived from the movement of the barrel, while the removal 20 of the cartridges from the holder is effected by the breech block during its running out movement, in the case of guns in which the barrel and breech block recoil are not positively connected with each other there is a danger of the 25 running out barrel advancing the cartridges in the holder into the path of the breech block before the breech in its backward movement has quite freed the cartridge inlet into the breech 30 chamber, that is to say when its front face has not yet arrived behind the line of the bases of 35 the cartridges in the holder. Consequently these cartridges will be damaged or the breech jammed, whereby the operation of the gun is interrupted or even more serious disturbances may occur.

It is an object of the present invention to overcome this drawback by subjecting the advance of the cartridges in the holder to a control by the movement of the breech block. According to the 40 invention a conveyer slide displaced by the movements of the barrel operates the actual cartridge holder through flexible intermediate members which store energy derived from the movements of the barrel, including a spring, for example, the stored energy in which is released in dependence on the recoil position of the breech block, to complete the advance of the cartridge holder. The breech block frees the advance movement of the holder, or at least the movement over the 45 last part of the feed track, when the front face of the breech block arrives behind the plane of

the ends of the cartridges in the holder. For this purpose there is arranged in line with the conveyer slide a second auxiliary slide carrying a pawl for advancing the holder. The movement of this auxiliary slide, which is under the influence of the spring tensioned by the conveyer slide, is checked by a stop located in the path of the conveyer movement. The abutment is moved by the breech block into the position which frees the advance movement of the auxiliary slide 10 only when the breech has run back sufficiently far to permit unhindered advance of the cartridges. The expanding spring is then able to thrust the auxiliary slide and the cartridge holder through the appropriate feed distance. 15

The accompanying drawing illustrates an example of construction of a cartridge feed according to the invention.

In the accompanying drawing Fig. 1 shows a longitudinal section through the part of the gun 20 containing the cartridge feed device.

Fig. 2 shows a cross section through the conveyer slide housing along the line 2—2 of Fig. 1.

Fig. 3 shows a horizontal section through the conveyer slide housing along the line 3—3 of 25 Fig. 1.

In the housing *a* of the gun there is mounted, in known manner, the barrel casing *b* forming the extension of the barrel, and in the casing *b* the breech block *c* is slidably mounted. The 30 cartridge feed device is accommodated in a box-like housing *a*₁ having open transverse walls for the passage of the cartridge holder *d*.

Transverse to the longitudinal axis of the gun there are mounted in the housing *a*₁ guides *a*₂, 35 *a*₂ in which the rigid cartridge holder *d*, which accommodates the cartridges *P* in sockets *p*₁, is adapted to be displaced transversely to the gun through recesses *a*₃, corresponding to the cross-section of the holder, formed in the housing *a* 40 and in the barrel casing *b* (Fig. 2). Above the holder *d* there are provided, transverse to the axis of the bore, longitudinal guides *e*, *e* for the conveyer slides *e*, *e* arranged symmetrically in the housing *a*₁. The slides *e*, *e* carry out, in 45 known manner, synchronous transverse movements from right to left and vice-versa, these movements being derived from the recoil and run-out movement. For this purpose toothed racks *e*₂, *e*₂ formed on the back surface of the 50 conveyer slide *e* mesh with pinions *f*₁, *f*₁ mounted on a sleeve *f* itself rotatably mounted in the housing *a*₁ and arranged in the longitudinal direction of the gun. The sleeve is rotated by a rod *g* mounted therein so as to be capable of 55

longitudinal displacement and attached by an arm b_1 to the barrel casing b , the said rod having a projection g_1 engaging in a helical groove f_2 in the sleeve f during the backward and forward movement of the barrel.

In order to attain the object of the invention it is of fundamental importance that the feed movement of the two conveyer slides e , e should not directly produce the movement of the cartridge holder d . With this object in view in a recess in each conveyer slide e there is provided a spring i which bears at one end against the conveyer slide e , and on the other end against an auxiliary slide h adapted to be displaced in guides h_1 formed in each slide e . The displacement of the auxiliary slide h inside the conveyer slide e in the direction of advance of the cartridges is limited by a pin e_3 (Fig. 2). The auxiliary slide h carries on a bolt k_1 a pawl k which is subjected to the constant downward pressure of a spring k_2 , and which, when in its downwardly pivoted position, engages in recesses d_1 in the holder d . These recesses d_1 are spaced on the back of the holder d , the spacing corresponding to the mean distance between the axes of two cartridges.

The head of the auxiliary slide h (see Fig. 3) is of step-wise formation so that two shoulders h_2 and h_3 are formed. The shoulder h_2 is adapted to cooperate with a stop m_1 which, according to the position of the breech c , lies opposite the shoulder h_2 so as to protrude into its path or lies opposite to the shoulder h_3 . The breech actuates the stop m_1 in such a manner that it will lie opposite the shoulder h_2 whenever the breech, in its recoil movement, is not in position behind the base of the cartridges P in the holder d , the advance movement of the holder d then being stopped; but the stop m_1 will lie opposite the shoulder h_3 , thus freeing the advance movement of the holder d , as soon as the breech c arrives behind the base of the cartridges. Two stops m_1 are disposed on a control rod m mounted at the end of the housing a_1 and adapted to be displaced in the longitudinal direction of the gun. The rod m is normally held by a spring n (Fig. 3) in the position wherein the steps m_1 obstruct the forward movement of the auxiliary slide h . At the rear end of the control rod m which is forked and which protrudes from the housing a_1 there engages a double-armed lever o pivotally mounted in the housing a of the gun, and the second arm of this lever protrudes into the path of a lug c_1 on the breech c . When the breech c , in its recoil movement, reaches a position in which its front face is approximately in line with the cartridge bases in the holder d , the lug c_1 strikes against the lever o and displaces the control rod m so far in the longitudinal direction of the gun that the stops m_1 come opposite to the shoulders h_2 and the advance of the holder d into its end position is no longer hindered by the auxiliary slide h . The spring i expands and thrusts the auxiliary slide h and with it the next cartridge into the holder d in front of the cartridge inlet. The mode of operation of the apparatus is as follows:

In the arrangement shown in Fig. 2 the cartridges are conveyed from left to right in front of the breech. When the barrel and the breech are in the full run out or forward position, the conveyer slide e and the auxiliary slide h are in their extreme right-hand position. On firing a shot, the backwardly moving barrel and barrel casing b move the conveyer slide e by means of the transmission members b_1 , g and g_1 , f_2 , f_1 , e_2

into its left-hand position while at the same time the pin e_3 carries along the auxiliary slide h . As the holder d , after each advance, is held firm in its advanced position by locking members not shown in the drawing; on the movement of the conveyer slide and the auxiliary slide into the left-hand end position, the pawl k slides over the back of the holder d and falls into the next rearwardly disposed notch d_1 of the holder d . On the subsequent run-out of the barrel and barrel casing b , the breech block c is still in the course of its recoil movement in the barrel casing. If in this backward movement of the block c its front face has not yet passed beyond the line of the bases of the cartridges in the cartridge holder d , the forward feed movement of the holder d , ceases, and a feeding movement which has already begun is interrupted. The first part of the feed path which is not blocked by the projection m_1 is determined by the distance of the projection m_1 from the shoulder h_2 (Fig. 3). In its feeding movement to the right, the auxiliary slide h runs against the stop m_1 and the holder d and with it the cartridges is held back until the projection m_1 is removed from the path of the shoulder h_2 , whereupon the auxiliary slide h can continue its forward movement into the end position under the influence of the spring i which in the meantime has been completely tensioned by the movement of the conveyer slide e . The projection m_1 is removed from the path of h_2 when the breech c has recoiled to such an extent that its front face lies behind the line of the cartridge bases, and the slide h , by the expansion of the springs i , moves the cartridge holder d into the correct end position for loading. In this manner the next cartridge is thrust into the path of the breech block which then runs forward, and thereby removes it from the holder d and thrusts it into the barrel.

I claim:

1. In a cartridge feed mechanism for machine guns having a sliding barrel and a longitudinally movable breech block adapted to thrust cartridges into the barrel chamber, the combination with a cartridge holder having ratchet teeth, of a conveyer slide driven by the barrel transversely to the axis thereof, a spring opposing movement of the conveyer slide in the cartridge feeding direction, an auxiliary slide between which and the conveyer slide said spring operates, a pawl on the auxiliary slide engaging the ratchet teeth on the cartridge holder, and a stop movable into and out of the path of the auxiliary slide and moved out of said path by the breech block when it has recoiled sufficiently to clear the path of feed of the cartridges.

2. Cartridge feed mechanism according to claim 1, in which the stop is actuated by the breech block by means including a projection on the breech block and a lever pivoted to a stationary part of the gun.

3. Cartridge feed mechanism according to claim 1, in which the barrel reciprocates the conveyer slide by means including rack teeth on said slide, a pinion engaging said rack and mounted in a stationary part of the gun, and connections between the barrel and the pinion for converting the to-and-fro movement of the barrel into an alternating rotation of the pinion.

4. In a cartridge feed mechanism for machine guns, a housing, a recoiling barrel mounted in the housing, a longitudinally movable breech block in the housing, a cartridge holder movable in the housing in a path transverse to the barrel axis,

- said cartridge holder having ratchet teeth thereon, a conveyer slide, transmission gear for reciprocating the conveyer slide in synchronism with the barrel movements, an auxiliary slide movable 5 positively by the conveyer slide in the opposite direction to feed movement of the cartridge holder, a pawl on the auxiliary slide engaging the ratchet teeth of the cartridge holder, a spring between the auxiliary slide and the conveyer 10 slide and arranged to be strained when the conveyer slide moves in cartridge feeding direction, a stop normally obstructing full movement of the auxiliary slide in said direction, and means actuated by the breech block when it has recoiled 15 sufficiently to clear the path of the cartridge feed for moving said stop out of the path of the auxiliary slide.
5. In a cartridge feed mechanism for machine guns having a sliding barrel and a longitudinally movable breech block adapted to thrust cartridges into the barrel chamber, the combination with a cartridge holder of means operated from the barrel and capable of advancing the holder to bring the cartridges therein successively to the 20 path of the breech block, said holder having a preliminary movement and a final movement in the cartridge feed direction, means for arresting movement of the holder at a predetermined point of its advance between the preliminary movement and the final movement, and means 25 for releasing the arresting means which is operated by the breech block when in its recoil the breech block has cleared the path of feed of the cartridges.
- 30 6. In a cartridge feed mechanism for machine guns having a sliding barrel and a longitudinally movable breech block adapted to thrust cartridges into the barrel chamber the combination with a cartridge holder of means operated from the barrel and capable of advancing the holder to bring the cartridges therein successively to the path of the breech block, said holder having a preliminary movement and a final movement in the car- 35
- 40

tridge feed direction, means for blocking the advance of the holder at a point between the preliminary movement and the final movement until the breech block has recoiled sufficiently to clear the feed path of the cartridges, and means operated by the breech block for releasing the blocking means for enabling the advance of the holder to be completed by energy derived from the barrel movement.

5

7. In a cartridge feed mechanism for machine guns having a sliding barrel and a longitudinally movable breech block adapted to thrust cartridges into the barrel chamber, the combination with a cartridge holder of means operated from the barrel for partially advancing the holder to bring the cartridges therein to the path of the breech block, said holder having a preliminary movement and a final movement in the cartridge feed direction, means for storing energy from the barrel movement, and means operated from the breech block upon the latter reaching a position in its recoil clear of the path of feed of the cartridges to complete the final advance of the holder by energy from the storing means.

8. In a cartridge feed mechanism for machine guns having a sliding barrel and a longitudinally movable breech block adapted to thrust cartridges into the barrel chamber, the combination with a cartridge holder of means including an elastic member operated from the barrel for advancing the holder to bring the cartridges therein successively towards the path of the breech block, said holder having a preliminary movement and a final movement in the cartridge feed direction, means for arresting the holder at the point of its advance between the preliminary movement and the final movement with resulting storage of energy from the barrel in said elastic member, and means for releasing the arresting means which is operated by the breech block when in its recoil it has cleared the path of feed of the cartridges.

40
